UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,279, dated August 30, 1898.

Application filed July 27, 1898. Serial No. 687,044. Term of patent 14 years.

To all whom it may concern:

Be it known that THOMAS MOORE, deceased, late a citizen of the United States, and a resident of Cheyenne, county of Laramie, and State of Wyoming, duly invented and produced a new and original Design for Buckles, of which the following is a full, clear, and exact description, reference being had to the accompanying drawing, forming a part hereof.

10 The figure is a plan view of a buckle embodying the design.

As shown in the drawing, the leading or material feature of the design consists of an elongated oval loop 1, the opposite parallel sides of which are slightly larger in diameter than are the rounded ends, and arranged a short distance from said loop 1 is an arm 2, that is slightly longer than said loop 1, and extending from the ends of said bar 2 to the

lower horizontal portion of the loop 1 are the 20 side bars 3. A pair of flanges 4 is formed upon the center of the bar 2, and extending from a point between said flanges 4 to the center of the lower one of the horizontal portions of the loop 1 is a bar 5, the same being 25 somewhat smaller in diameter than is the remainder of the frame of the buckle.

What is claimed is—

The design for a buckle, substantially as herein shown and described. 30

In testimony whereof I affix my signature in presence of two witnesses.

LEOPOLD KABIS,
Administrator of Thomas Moore, deceased.

Witnesses:

WALTER R. STOLL,
WM. R. SCHNITGER.
